UNITED STATES PATENT OFFICE.

ROLLIN C. LEWIS, OF STAMFORD, CONNECTICUT, ASSIGNOR TO THE YALE & TOWNE MANUFACTURING COMPANY, OF STAMFORD, CONNECTICUT.

PERMUTATION LOCK DEVICE.

1,286,670.

Specification of Letters Patent.

Patented Dec. 3, 1918.

Application filed November 15, 1916. Serial No. 131,437.

To all whom it may concern:

Be it known that I, ROLLIN C. LEWIS, a citizen of the United States, and a resident of Stamford, in the county of Fairfield and

5 State of Connecticut, have invented certain new and useful Improvements in Permutation Lock Devices; and I do hereby declare the following to be a full, clear, and exact description of the invention, such as will 10 enable others skilled in the art to which it appertains to make and use the same.

This invention relates to improvements in permutation lock devices, and more particularly to such as are adapted to control 15 the operation of electrical switches, one object of the invention being to provide simple and efficient means, in a lock structure of the type specified, which will prevent access, by unauthorized persons, to the 20 switch or other devices which the lock controls.

A further object is to provide a lock-switch mechanism wherein permutation lock devices are employed and in which the fence 25 which coöperates with said lock devices shall be connected with the movable member of the switch devices, so that when the permutation devices are properly set to be interlocked with the fence, the movable member 30 of the switch devices may be actuated by a continued turning of the dial knob.

A further object is to provide a permutation lock in which the dial, dial ring and tumblers shall be combined in a single structure or unit and provided with means whereby the removal of this structure shall be 35 controllable by operation of the permutation lock devices and a movable member coöperable therewith.

40 With these and other objects in view, the invention consists in certain novel features of construction and combinations of parts as hereinafter set forth and pointed out in the claims.

45 In the accompanying drawings; Figure 1 is a face view of a lock structure embodying my invention; Fig. 2 is a transverse sectional view taken between the permutation devices and the switch devices; Fig. 3 is a 50 bottom plan view of the unitary structure embodying the dial, curb, dial ring and tumblers and the curb locking device; Fig. 4 is a sectional view of the structure shown in Fig. 3; Fig. 5 is a sectional view, partly 55 in elevation, of the complete lock switch;

Fig. 6 is a detail view showing the switch arm and fence connected therewith, and Fig. 7 is a detail view of the curb locking device.

1 represents a base of suitable insulating material and on which the lock housing 2 is mounted, said housing being provided with an opening having internally threaded annular flange 3 to receive the threaded portion 4 of a tumbler curb 5. The housing 60 is secured to the base block 1, by means of pins or posts 6 which pass through said block and through lugs 7 secured to the housing 2, said pins or posts being provided near their inner ends with suitable 65 transverse holes for the reception of cotter pins or keys 8. It is apparent that the keys 8 cannot be removed to remove the housing from the base without first removing the curb from the housing and this cannot be 70 accomplished by unauthorized persons, as 75 will be hereinafter explained.

The curb 5 is made with a central sleeve 9 which serves as a mounting for permutation tumblers 9^a and also to receive and 80 provide a mounting for a collar or annular enlargement 10 on the lock spindle 11. This spindle is threaded throughout a portion of its length to receive the internally threaded hub 12 of the cam plate or disk 13, the 85 latter being secured to the spindle 11 by means of a key or screw 14 and adapted to transmit motion to the tumblers in a manner which is well understood. The tumblers are made with notches 15 as is also the cam plate 90 or disk 13 and when these notches are brought into alinement with each other by certain manipulation of the tumblers, said notches will receive a device which will lock the tumblers to the curb, and when said 95 notches are brought into alinement by another manipulation of the tumblers, they will receive a device which will connect the tumblers with the switch devices.

The spindle 11 is provided with a knob 100 16 which serves to clamp a dial 17 to said spindle, the peripheral portion of said dial entering the recessed outer face of the curb. The peripheral portion of the curb thus forms a dial ring 18, and this ring is provided at points located (in the present instance) 90 degrees apart, with marks 19 and 20 with which the graduations on the dial may be caused to register.

Diametrically opposite the mark 19 a curb 110

locking device 21 is located. This device comprises an arm 22 having a slot 23 for the accommodation of a screw 24 whereby the curb lock may have sliding connection 5 with the curb. The curb locking slide 21 also comprises a finger 25 which projects beyond the dial ring to permit manual manipulation of said slide to move the same into or out of the notches 15 of the tumblers 10 9^a and disk 13. The locking slide 21 is made with a shoulder 26 which, when the slide is moved out of engagement with the notches 15, will enter a notch 27 in the housing 2, and thus prevent the curb and 15 the parts carried thereby from being removed from the housing. Movement of the slide from the locked position above described will be prevented by the tumblers 9^a and disk 13, and said slide can be detached 20 from the housing only when the notches 15 are brought into alignment and this cannot be accomplished by anyone not familiar with the proper combination to bring about such alignment opposite said slide. When 25 the lock shall have been operated with the proper combination (using the indicator mark 19 on the dial ring) to bring the notches 15 into alignment opposite the locking device 21, the latter can then be moved 30 out of engagement with the housing and into the notches 15, thus locking the tumblers 9^a and disk 13 to the curb and permitting the latter to be unscrewed from the housing. 35 The switch devices may be adapted for any desired number of electrical connections. In the drawings, I have shown four contact plates 28 disposed in circular arrangement and secured to the insulating 40 base block 1 and suitably spaced apart. A movable contact member 29 (which may comprise superposed spring plates) is secured to an insulating block 30 mounted to turn on a pin 31 passing through the base 45 block 1. The contact member 29 may be made with two fingers 32-33 to move over the contact plates 28, and one of these fingers may be provided with a ball 34 to move over said contact plates or become disposed 50 between the adjacent ends of two of them. Stop pins 35 may be provided to limit the movements of the movable switch member. 55 The revolute block 30 is provided with an arm 36 with which a fence 37 is pivotally connected. A spring 38 tends to press said fence toward the tumblers and the latter serve to retain a lug 39 carried by said fence in a notch 40 in the flange of a curved plate 41 secured to the base block 1,—thus 60 normally preventing movement of the switch member 29.

When the permutation lock shall have been so operated (using the indication mark 20 on the dial ring in effecting the combination 65 as to bring the notches 15 of the tum-

blers 9^a and disk 13 into alignment with each other and with the fence 37, the latter will be forced by its spring 38 into the aligned notches, thus connecting the tumblers with the movable switch member, so that 70 continued movement of the knob dial, in either direction, will effect the operation of the switch as may be desired.

Various changes might be made in the details of construction of my invention without departing from the spirit thereof or limiting its scope and hence I do not wish to restrict myself to the precise details herein set forth.

Having fully described my invention, what 80 I claim as new and desire to secure by Letters-Patent, is:—

1. In a combination lock, the combination of a housing, a curb having threaded connection with the housing, a dial and tumblers mounted on and carried by the curb so as to be removable therewith, and a manually operable locking device carried by the curb and controlled by the tumblers for locking the curb against removal except 90 when the tumblers have been set to permit of movement of the locking device and for locking the tumblers against rotation on the curb.

2. The combination with a housing, a curb having threaded connection with the housing, tumblers at the rear of the curb and manually operable means carried by the curb and controlled by the tumblers for locking the curb against removal except 95 when the tumblers have been set to permit of the movement of the locking device and for locking the tumblers against rotation on the curb.

3. The combination of a housing, a curb 105 screwed to the housing, tumblers carried by the curb, tumbler actuating means, and manually operable means carried by the curb, and controlled by the tumblers for locking the curb against removal except 110 when the tumblers have been set to permit of the movement of the locking device.

4. The combination with a housing, of a curb having removable connection therewith, a dial carried by said curb, tumblers also 115 carried by said curb, a spindle connected with the dial, a disk secured to the spindle and co-operable with the tumblers, and a locking device carried by the curb and co-operable with the housing and with the 120 tumblers and said disk.

5. The combination with a housing, of a combination lock attached to said housing, a fence co-operable with the combination lock for actuating a switch located within the 125 housing, and a locking device for said combination lock, said locking device being co-operable with the housing and with the combination lock and having a part projecting beyond the housing.

6. The combination with a housing, a combination lock, and means for connecting the tumblers of said combination lock with a movable member when said lock is set in accordance with a predetermined combination, of a locking device carried by the combination lock and coöperable with the housing, said locking device being also coöperable with the tumblers of the combination lock in accordance with a different predetermined combination to permit the unlocking of the combination lock from the housing and locking the tumblers to the curb of said combination lock, said lock device having a part projecting beyond the housing, whereby it may be manually operated.

7. The combination with a housing, a combination lock attached to the housing, and a part to be moved by the lock, of a spring-actuated fence pivotally connected with the part to be moved and adapted for coöpera-

tion with the tumblers of the combination lock, said fence having a projection, and a curved member in the housing having a notch to receive the projection on said fence.

8. The combination with a housing, a combination lock attached thereto and a part to be moved by the combination lock, of a fence attached to said part to be moved and coöperable with the tumblers of the combination lock, and a locking device controlled by the combination lock for locking the latter to and unlocking it from the housing, said locking device having a part to project beyond the casing whereby it may be operated manually.

In testimony whereof, I have signed this specification in the presence of two subscribing witnesses.

ROLLIN C. LEWIS.
